COLLECTING ELECTRODE FOR ELECTRICAL PRECIPITATORS

Floyd H. Viets, Glendale, Calif., assignor to
Western Precipitation Corporation, Los Angeles,
Calif., a corporation of California

Application December 30, 1943, Serial No. 516,156

2 Claims. (Cl. 183—7)

This invention relates to collecting electrodes of electrical precipitation apparatus for use in the separation of suspended material from gases, and particularly to collecting electrodes of the type in which a thin film of liquid is passed, preferably continuously, over the collecting electrode surfaces on which the material is precipitated.

More specifically, the invention is concerned with liquid-flushed collecting electrodes comprising vertical pipes or tubes. Such collecting electrodes are ordinarily assembled within a housing and mounted adjacent their upper ends on a horizontally extending wall or header plate. The gas is passed vertically through the collecting electrode pipes, and an opposing precipitating electrode extends centrally within each pipe. Water or other suitable liquid is supplied to the space around the upper ends of the collecting electrodes above the header plate, and flows over the upper edges of these electrodes and down the inside surfaces thereof, on which the material is precipitated. The space above the header plate constitutes a liquid supply chamber or reservoir, and the upper ends of the collecting electrodes extend upwardly above the header plate and act as overflow lips or weirs to control the flow of water into each electrode.

An electrical precipitator of this general type is shown in United States Patent of Crowder et al. No. 1,968,334, issued July 31, 1934. Such liquid-flushed pipe collecting electrodes are useful in precipitators of the single-stage type, as disclosed in the above mentioned patent, in which the precipitating electrodes within the pipes are discharging electrodes such as small diameter wires, or rods provided with sharp edges or points, whereby a corona discharge is maintained for the purpose of both charging and precipitating suspended particles in the electric field between these electrodes and the collecting electrodes.

Similar liquid-flushed collecting electrodes are also useful in electrical precipitators of the two-stage type, in which the charging and precipitating of the suspended material are carried out in successive spatially separated fields. In this case the precipitating electrodes within the pipes may comprise non-discharging electrode members of extended surface, such as smooth rods or pipes of sufficient diameter to substantially avoid corona discharge; or the precipitating electrodes may comprise composite electrode elements provided with both discharging and non-discharging portions, as shown for example in United States patent of Anderson, No. 2,192,172, issued March 5, 1940.

Electrical precipitators of the types above described are well known in the art. The present invention is concerned only with an advantageous form of collecting electrode for use in any type of precipitator employing liquid-flushed tubular or pipe collecting electrodes, and it will be understood that such electrodes may be used in connection with any type or form of opposing precipitating electrode.

10. The collecting electrode pipes are generally of substantially uniform diameter throughout the major portion of their height to provide the desired spacing of the collecting surface, and the liquid film thereon, from the opposing electrode.
15. It is desirable that this portion of the collecting electrode surface be free from sharp edges or other irregularities or discontinuities that would tend to disturb the smooth flow of the liquid film or to cause electrical discharge from the collecting electrode. It is also desirable that the upper end portion of the collecting electrode including the overflow lip or weir at which the liquid film is formed, as well as the lower end portion of the collecting electrode where the liquid leaves the collecting surface, be of materially greater diameter than the major portion of the pipe, so as to prevent electric discharge from the ends of the collecting electrode and to provide for forming and breaking the liquid film at positions of reduced electric field strength.

The principal object of this invention is to provide a simple and inexpensive collecting electrode structure that meets all of the above requirements and provides all of the above-mentioned desired features.

A particular object is to provide a collecting electrode structure of the type above described, having a flared lower end member removably mounted on the bottom of the pipe and flared 40 downward and outward, whereby the electrode may be assembled in the precipitator by passing the electrode pipe downward through an opening in the header plate, after which the lower end member may be secured thereto, so that the 45 opening in the header plate need be of only sufficient diameter to receive the pipe.

In accordance with this invention, the collecting electrode comprises a pipe, preferably of substantially uniform diameter throughout the major portion of its length, having its upper end portion flared outward so that the inside diameter of the upper edge of the pipe is materially greater than that of the major portion of the pipe. A weir ring member is adjustably mounted around 55 the upper end of the pipe, and extends upward

above the pipe. The weir ring is in close sliding engagement with the upper end of the pipe, so as to provide a substantially liquid-tight fit at that point while still permitting vertical and angular adjustment of the weir ring relative to the pipe, and suitable means are provided for effecting such adjustment.

As noted above, the pipe is preferably provided at its lower end with a flared end member detachably secured thereto, which may be formed as a ring whose inner surface is flared downward and outward. The inner face of this ring is preferably recessed outward at the upper portion of the ring, to receive the lower end of the pipe and provide a substantially smooth continuous inner surface at the juncture of the pipe and the ring.

The accompanying drawings illustrate a preferred form of collecting electrode, according to my invention, and referring thereto:

Fig. 1 is a partial vertical section of an electrical precipitator, with several collecting electrodes and associated precipitating electrodes shown in elevation;

Fig. 2 is a horizontal section on line 2—2 in Fig. 1;

Fig. 3 is a vertical section showing the upper end portion of one of the collecting electrodes, taken on line 3—3 in Fig. 2;

Fig. 4 is a horizontal section on line 4—4 in Fig. 1; and

Fig. 5 is a vertical section of the lower end portion of one of the collecting electrodes, taken on line 5—5 in Fig. 4.

A plurality of tubular collecting electrodes 1 are shown as extending vertically through and supported upon a header plate 2, it being understood that these electrodes are ordinarily mounted within an enclosed precipitator housing provided with gas inlet and gas outlet means at opposite sides of the header plate so as to provide for passage of gas to be treated, vertically through the several electrodes, as more fully shown and described in the above-mentioned United States Patent 1,968,334.

Each collecting electrode comprises a pipe 3 of suitable length and diameter, which is of substantially uniform diameter throughout the major portion of its length. The upper end of the pipe extends above the header plate 2, and is flared outwardly as shown at 4 to provide an upper edge 5 of materially greater inside diameter than the major portion of the pipe. At the upper edge the external surface of the pipe is preferably finished so as to provide a short cylindrical bearing surface 6.

Each of the collecting electrode pipes extends through an opening 8 in header plate 2 and is shown as supported on said header plate by means of an outwardly projecting annular flange 9 welded or otherwise secured to the pipe and supported on the header plate. A suitable gasket 10 is preferably provided between flange 9 and header plate 2 and the flange is shown as secured to the header plate by means of bolts 11, thus providing a fluid-tight connection between the header plate and each pipe.

An adjustable weir ring 12 is mounted in position around the upper end of each pipe 3, with its cylindrical inner surface in close sliding engagement with cylindrical face 6 on the pipe. Ring 12 extends upward above the upper edge 5 of the pipe and its upper edge 13 may be either plain as shown or may, if desired, be notched or serrated as shown for example in Fig. 7 of said Patent 1,968,334. Means are provided for sup-

porting and adjusting the weir ring, comprising for example four adjusting screws or bolts 15, extending through outwardly projecting members such as lugs 16 at equally spaced positions around the ring and provided with heads 17 and nuts 18 bearing against the upper and lower faces respectively of said lugs. The lower ends of adjusting screws 15 engage nuts or other internally threaded members 19 welded or otherwise secured to flange 9. Thus, by suitable manipulation of screws 15 and nuts 18 the weir ring 12 may be raised or lowered at the position of each adjusting screw, so as to provide vertical adjustment of the weir ring relative to pipe 3 and also for vertical angular adjustment of said ring relative to said pipe. Although the ring fits quite closely about the external face 6 at the upper end of the pipe in order to provide a substantially liquid-tight engagement, the relationship is such as to permit some angular tilting of the ring relative to the pipe. It will be observed that the vertical dimension of face 6 is quite short relative to the diameter thereof so as not to unduly limit such tilting movement, and the fit at this point need not be extremely close in order to substantially prevent leakage of liquid between the pipe and the ring.

Each collecting electrode is also provided at its lower end with a ring 21, removably secured thereto as by means of set screws 22. The lower portion of ring 21 has its inner surface flared downward and outward as indicated at 20, so that the inside diameter of the lower end 23 thereof is materially greater than that of the major portion of pipe 3. At the upper portion of ring 21 the inner surface is recessed outward as shown at 24, to a depth substantially equal to the wall thickness of pipe 3, so as to receive the lower end of said pipe with the internal surfaces of the pipe and ring substantially flush with each other and provide a substantially smooth continuous internal surface at the juncture of the inner surfaces of the pipe and ring, as indicated at 25. In erecting the apparatus, the collecting electrode pipes 3 are passed from above through the openings 8 in the header plate, which openings need be of only sufficient size to receive the main portion of the pipes, and the lower end rings 21 are thereafter secured to the pipes.

The lower ends of the pipes are shown as held in properly spaced and vertically aligned position by means of adjusting screws 27 engaging nuts or other internally threaded members 28 which are secured to small plates 29 supported by suitable frame members 30.

The precipitating electrodes are shown as comprising discharge electrode members 31, such as wires or square twisted rods extending axially through the collecting electrodes and supported at their upper ends by suitable supporting frame means such as indicated at 32, 33 and 34. Spacing means 35, carried by frame members 36 are provided for alining the lower ends of the discharge electrodes 31, and said electrodes may also be provided at their lower ends with tensioning weights 37 secured thereto by rods 38. Said rods 38 are preferably of sufficient diameter to prevent corona discharge therefrom, and preferably extend upward to a position above the lower ends of the collecting electrodes.

The collecting electrodes are ordinarily maintained at ground potential, while the entire discharge electrode system including discharge electrodes 31 and the associated supporting and spacing means is mounted on insulating supports, so

that the necessary high potential may be maintained between the discharge and collecting electrodes to cause corona discharge from discharge electrodes 31.

The space above the header plate 2 serves as a liquid reservoir, and this space may be divided into a plurality of separate liquid supply compartments or troughs, as by means of suitably spaced walls 41 extending upwardly from header plate 2 to a position somewhat above the upper edges or overflow lips 13 of the weir rings. A plurality of collecting electrodes are arranged with their upper ends within each of the liquid supply compartments or troughs thus provided between adjacent walls 41. Liquid is supplied through pipes 42 and downwardly extending nipples 43 which deliver the liquid above the header plate and below the weir rings 12, preferably at positions between each set of four collecting electrodes as indicated in Fig. 2.

After the apparatus is erected, the liquid to be used for flushing, which may be either water, oil, or any other suitable liquid, is supplied to each of the compartments defined by walls 41, and the weir rings 12 of the several electrodes in each such compartment are then carefully adjusted as described above, in order to provide substantially equal flow of liquid into the respective electrodes and also for substantially uniform flow of liquid at all circumferential positions around the upper edge of each of the weir rings. This provides for maintaining a substantially uniform downward flow of liquid through all the electrodes in a thin film distributed substantially uniformly over the entire inner surface of each electrode.

The liquid film is formed at the upper edge of the weir ring, at a position spaced from the opposing precipitating electrode 31 by a distance

materially greater than the spacing between the precipitating electrode and the major portion of the inner surface of the collecting electrode, so as to avoid electrical disturbances, and the same 5 considerations apply where the liquid leaves the collecting electrode surface at the lower edge 23 of bottom ring 22. The entire surface over which the liquid flows, between the top and bottom edges of each collecting electrode, is free from 10 sharp edges or surface discontinuities or irregularities that might tend to disturb the smooth flow of the liquid or to cause electrical disturbances.

Although the precipitating electrodes are in 15 this case shown as discharge electrodes, it will be understood that the collecting electrode structure of this invention may also be employed with non-discharging precipitating electrodes as brought out hereinabove.

20 I claim:

1. A collecting electrode for use in liquid-flushed electrical precipitators, comprising: a vertically extending pipe of substantially uniform inside diameter throughout the major portion 25 of its length and having its upper end portion flared outward to provide an upper edge of materially increased diameter; and a ring removably mounted on the lower end of said pipe and flared downward and outward, the lower end of 30 said ring having an inside diameter materially greater than said major portion of the pipe.

2. A collecting electrode as set forth in claim 1, the upper end of said ring being recessed internally, and the lower end portion of said pipe extending within the recess in the ring with the 35 inner surfaces of the pipe and ring substantially flush with each other at the juncture thereof.

FLOYD H. VIETS.
